UNITED STATES PATENT OFFICE.

WILLIAM C. OSTERHOLM, OF OAK PARK, ILLINOIS, ASSIGNOR TO WILCOX PRODUCTS CORPORATION, OF SAGINAW, MICHIGAN, A CORPORATION OF MICHIGAN.

VALVE TAPPET, AND METHOD OF FORMING THE SAME.

Application filed December 14, 1925. Serial No. 75,409.

The invention relates to the manufacture of valves, valve tappets and the like and has for its object the obtaining of a structure built up from a separately formed head 5 and stem and having properties particularly adapted for its use in internal combustion engines. The present invention is an improvement over that described in my co-pending application Serial Number 708,048, filed April 21, 1924.

In the prior application above referred to, the head and stem are united by mechanical processes but I have now improved the construction by providing in addition to the 15 mechanical interlock of the parts a bond which more securely holds them together in fixed relation. Furthermore, I have provided a tappet in which the head and shank are given different physical properties, each 20 suitable for its own function, the head having a hard wear-resisting surface and the shank having greater strength and being less brittle. These properties are imparted to the structure by selection of suitable 25 materials for the stem and head and in finally subjecting the finished tappet to a single heat treatment that is equally beneficial for both materials.

In the drawings:

Figure 1 illustrates the separate stem and head and the method of uniting the same;

Figure 2 is a plan view of the head;

Figure 3 is a plan view of the brazing ring;

Figure 4 is a longitudinal section through the completed tappet.

The head A of my improved tappet is preferably made of malleable iron, which in its usual physical condition may be formed into the shape illustrated in Figure 1 by forging, casting or machining. The head is preferably formed with an annular recess B, the outer circumferential edge C of which is under cut to form a shoulder as illustrated. The bottom of the recess is curved inwardly and upwardly as indicated at D forming the annular central portion or flange E. The central portion of the tappet 45 contains the cup-shaped recess F communicating with the central aperture G extending through the head and forming the means for feeding the lubricant onto the associated cam with which the tappet cooperates.

The tappet stem H may be formed in various ways, but is preferably tubular as in-

dicated and has the lower end of the tubular portion flared outwardly as indicated at I to extend in a plane substantially transverse to the axis and then downwardly forming the tubular end portion J. The outer diameter of the portion J is substantially the same as the inner diameter of the flange K on the head, while the inner diameter of the portion J is greater than that of the flange E on said head.

In order to assemble the stem to the head, the latter is placed in a suitable holder L while the former is held in a co-operating holder M, the arrangement being such as to permit pressure to be exerted between said 70 holders. At the beginning of the assembling operation it will be noted, from Figure 1 of the drawing, that the flared portion I of the stem is in a position relatively oblique to the surface formed by the recess B on the head. The holder M has an annular nose N engaging the outwardly flared portion I of the stem and when pressure is applied to the holder the flange J is turned 75 to engage the undercut portion C of the head 80 and is expanded to form an inter-locking engagement therewith. This inter-locking is facilitated by the angular movement of the flange J which expands the lower portion thereof to a greater diameter than the 85 upper portion conforming to the shape of the undercut wall. The stem is also caused to conform with the curved portion D of the annular recess thereby entirely filling 90 the same without forming any sharp bends. Figure 4 shows the tappet after the interlocking of the head and stem and it will be 95 noted that the flange J has been turned to extend radially outward and lies substantially in a plane perpendicular to the axis of the stem.

As stated above, it is desirable to provide a bond between the head and stem and this is accomplished in the present instance by inserting a brazing material in the recess 100 prior to the application of the pressure. The brazing material is preferably introduced by providing the flat ring-shaped disc O, the outer diameter of which corresponds to the inner diameter of the flange J and the inner diameter being larger than the annular flange E. Thus the disc may be inserted in the recess B beneath the stem H, after which the pressure is applied to the 105 holder M as heretofore described, forming 110

2
a mechanical inter-locking of the parts in such a manner as to inclose the disc in the joint. In order to complete the bond between the stem and head the assembled tappet is heated to a brazing temperature, whereupon the brass disc is melted and the molten brazing material distributed into the crevices of the joint and upon solidification forms a brass film Q, as indicated in

10 Figure 4.

It is desirable that the valve tappet be heat treated in order to harden the head and refine the stem and in the preferred process the heat treatment and the brazing are carried out simultaneously. The assembled tappets are therefore heated to a temperature sufficiently high to harden both the head and the stem, this temperature also being sufficient to melt the brazing material. To facilitate the brazing the tappet is momentarily withdrawn from the heating furnace and emersed in a flux such as molten sodium cyanide which readily enters the crevices of the joint opened by the heating. The tappet is then replaced in the heating furnace and brought up to the required temperature, after which it is quenched to harden the tappet and to solidify the brazing material. The temperature used in the heat treatment depends upon the type of materials used, but where the head is of malleable iron and the stem is a medium carbon steel having for example, .35% of carbon, a suitable treatment is to heat to 1550° F., and quench in oil. This treatment imparts an extremely hard surface to the malleable head A and also hardens the stem H sufficiently to impart wear-resisting qualities thereto. This temperature, however, is sufficiently low to prevent overheating of the stem so that it will not be unduly brittle. Thus with a single heat treatment the head and stem are bonded together and are also provided with desirable physical properties for insuring long life under service requirements.

The outer surface R of the stem H is ground in the usual manner for engagement with the co-operating guide and the bottom surface S of the head is also ground to operate with the cam. The method of assembling the stem to the head results in the portion of the stem adjacent the head being forced slightly inward thereby resulting in a clearance groove T. The tappet as above described is cheap to manufacture and has the desirable physical properties for long life and useful service.

What I claim as my invention is:—

1. The method of manufacturing valve tappets and the like comprising the separate forming of a head member and a tubular stem member, said stem member having an annular end portion which is relatively oblique to a surface on said head member, and said head member being undercut ad-

jaacent said surface, inserting said stem into said head, placing a brazing material between the same, applying endwise pressure to said members whereby the end portion of said stem is forced into inter-locking engagement with the undercut portion of said head member and heating said head to effect a brazing of said head and stem.

2. The method of manufacturing valve tappets and the like comprising the separate forming of a head member and a tubular stem member, said stem member having an annular end portion which is relatively oblique to a surface on said head member and said head member being formed with a recess having an undercut peripheral portion, inserting an annular brass disc in the recess of said head having a diameter adapted to also fit within the annular end portion of said stem, applying endwise pressure to said members to expand said annular end portion into conformity with said recess and heating said head to melt said brass disc and to distribute the molten brass between the contacting portions of said members.

3. The method of manufacturing valve tappets and the like comprising the separate forming of a head of malleable iron, and a tubular stem of medium carbon steel, said head having an undercut recess and said stem having a co-operating annular end portion, inserting said stem into said head with brazing material therebetween, applying endwise pressure to said members sufficient to force said end portion into inter-locking engagement with said undercut portion, heating the united head and stem to a temperature sufficient to melt said brazing material, harden said head and refine said stem, and quenching the head portion of the united product.

4. A tappet comprising a head member recessed to form a shoulder, a tubular stem provided with an annular flange at one end thereof extending substantially in a plane perpendicular to the axis of said stem and inter-locking with said shoulder, and a film of bonding material between the contacting portions of said head and stem.

5. A tappet comprising a head member recessed to form a shoulder, a tubular stem provided with an annular flange at one end thereof extending substantially in a plane perpendicular to the axis of said stem and interlocking with said shoulder, and a brass film between adjacent portions of said stem and head forming a bond between the same.

6. A tappet comprising a disc head recessed to form an annular undercut shoulder, an inwardly and upwardly extending curved surface and a central concave surface having an aperture centrally thereof, a tubular stem provided with an annular flange at one end thereof extending substantially in a plane perpendicular to the axis and periph-

- erally inter-locking with said undercut shoulder, said flange being rounded as it merges into the body of the tubular stem to fit the curved surface of said head, and a film of bonding material between said stem and head, said film being united to said undercut shoulder, said inwardly extending curved surface and said tappet stem.
7. A tappet comprising a disc head of hardened malleable iron, said head being recessed to form an annular undercut shoulder, an inwardly and upwardly extending curved surface, and a central concave surface having an aperture therein, a tubular stem of medium carbon steel provided with an annular flange at one end thereof extending substantially in a plane perpendicular to the axis and peripherally interlocked with said undercut shoulder, said flange conforming to the contour of said recess, and a brass film intermediate said flange and said head forming a bond between the interlocking portions of said members.
8. The method of manufacturing valve tappets and the like comprising the separate forming of a metallic head member and a metallic stem member, said head member having an undercut recess therein, inserting brazing material into said recess, applying endwise pressure to said members, whereby the end portion of said stem is forced into inter-locking engagement with the undercut portion of said head member and the brazing material is inclosed within the joint and subsequently heat treating the assembled members to harden one of the same and to form a brazed joint.
9. A tappet or the like comprising a head member recessed to form an annular undercut shoulder and a curved lower surface, a tubular stem provided with an annular flange one end thereof extending substantially in a plane perpendicular to the axis and peripherally interlocking with said undercut shoulder, said flange also conforming to the rounded lower surface of said recess, and a film of bonding material between said stem and head.
10. The method of manufacturing a valve tappet which consists in separately forming a metallic head member and a metallic stem member, inserting a brazing material between said head member and the said stem member, locking the said head member and the said stem member together and subsequently heat treating the assembled members to harden the same and to form a brazed joint between the same.
11. The method of manufacturing a valve tappet which consists in separately forming a metallic head member and a metallic stem member, forming interlocking means on the said members, inserting a brazing material between the said members, locking the two members together with the brazing material therebetween, and subsequently heat treating the said members to harden the same and to form a brazed joint between the same.
12. The method of manufacturing a valve tappet which consists in separately forming a metallic head member and a metallic stem member, forming a shoulder on the head member, forming means on the stem member adapted for interlocking engagement with the said shoulder, inserting a brazing material between the said members, locking the said members to each other with the brazing material therebetween, and subsequently heat treating the said members to harden the same and to form a brazed joint therebetween.
- In testimony whereof I affix my signature.
- WILLIAM C. OSTERHOLM.
